CLAIM

The ornamental design for a food cutter, as shown and described.

DESCRIPTION

FIG. 1 is a perspective view of the food cutter.

FIG. 2 is a front view of the food cutter as shown FIG. 1.

FIG. 3 is a back view of FIG. 1.

FIG. 4 is a left side view of FIG. 1.

FIG. 5 is a right side view of FIG. 1.

FIG. 6 is a top view of FIG. 1.

FIG. 7 is a bottom view of FIG. 1.

FIG. 8 is a perspective view a second embodiment of the food cutter.

FIG. 9 is a front view of the second embodiment as shown in FIG. 9.

FIG. 10 is a back view of the second embodiment as shown FIG. 9.

FIG. 11 is a left side view of the second embodiment as shown FIG. 9.

FIG. 12 is a right side view of the second embodiment as shown FIG. 9.

FIG. 13 is a top view of the second embodiment as shown FIG. 9; and,

FIG. 14 is a bottom view of the second embodiment as shown FIG. 9.

The broken lines present in the drawings are for illustrative purposes and form no part of the claimed design.
